Primary Examiner — T Chase Nelson*Assistant Examiner* — Jeff Lenard D Torres(74) Attorney, Agent, or Firm — Finnegan, Henderson, Farabow, Garrett & Dunner, LLP(57) CLAIM

The ornamental design for footwear, as shown and described.

DESCRIPTION

FIG. 1 is a front elevation view of footwear showing the new design;

FIG. 2 is a rear elevation view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top, left perspective view thereof; and,

FIG. 8 is a top, right perspective view thereof.

The dot-dash lines illustrate the boundary of the claimed design and form no part thereof. The portions of the figures outside of the dot-dash line shown in lighter contrast illustrate other portions of the footwear and form no part of the claimed design.

1 Claim, 8 Drawing Sheets(56)
